UNITED STATES PATENT OFFICE.

CHARLES F. GUARD, OF PHOENIXVILLE, PENNSYLVANIA.

BOTTLE STOPPER.

1,425,009.

Specification of Letters Patent. Patented Aug. 8, 1922.

Application filed September 27, 1919. Serial No. 326,732.

To all whom it may concern:

Be it known that I, CHARLES F. GUARD, a citizen of the United States, residing at Phoenixville, in the county of Chester and State of Pennsylvania, have invented certain new and useful Improvements in Bottle Stoppers, of which the following is a specification.

This invention relates to bottle stoppers, and more particularly to a combined bottle stopper and medicine dropper which is applicable for use upon bottles of approved type, as well as one which is particularly adapted for use in connection with bottles containing poison, and which will prevent children or other persons from accidentally drinking the contents of the bottle.

More specifically, the invention comprehends the provision of a bottle stopper structure including an elongated plug adapted to extend downwardly into a bottle, which plug is provided with a longitudinal groove adapted to serve as a passageway to permit the dropping of the contents of the bottle therefrom, also to mount a cork about a portion of the stem for fitting and closing the mouth of the bottle as well as to provide a novel wire attaching structure, for attaching the improved stopper to a bottle, in such manner that the stopper may be moved longitudinally relative to the bottle within certain limits, to permit it to be used as a dropper in dispensing the contents of the bottle, which wire structure is bent to form a stopper engaging portion, and a pair of parallel legs having their end portions bent to engage about the outer surface of the neck of the bottle and against the under surface of the flange formed in the upper neck of the bottle to attach the stopper structure to the bottle and to form means for limiting the relative movement of the stopper and bottle.

Other objects of the invention will appear in the following detailed description taken in connection with the accompanying drawings, forming a part of this specification and in which drawings:

Figure 1 is a side elevation of the im-

proved bottle stopper showing the same applied to a bottle.

Figure 2 is a side elevation of the improved stopper showing it applied to a fragment of a bottle and in position to permit the dispensing of the contents of the bottle by drops.

Figure 3 is a fragmentary horizontal section through the dropper structure illustrating the manner of connecting the attaching wire structure thereto.

Figure 4 is a horizontal section taken on the line 4—4 of Figure 2.

Figure 5 is a side elevation of the stem of the stopper illustrating the cork thereof in section.

Figure 6 is a horizontal section taken on the line 6—6 of Figure 2.

Referring more particularly to the drawings, wherein like characters indicate like and corresponding parts throughout the several views, the bottle A, may be of any approved type of bottle commonly used for dispensing or marketing medicines or analogous liquid, and this bottle is provided with the usual neck B upon the outer end of which is formed the annular flange C.

The improved stopper structure 10, comprises a stem 11, preferably formed of glass, or analogous material, which is provided with a reduced portion 12, formed thereon near its upper end, and a cork 13 is mounted about this reduced portion, either by splitting the cork as shown at 14, or in any other practical manner. The stem 11 is slightly smaller in diameter than the interior of the neck B of the bottle, and it is provided with a longitudinally extending groove 15, which is adapted to permit the liquid contents of the bottle A to be dispensed in drops, thereby eliminating the use of the usual type of medicine dropper when the improved form of stopper is employed.

An attaching structure 16 is provided for attaching the stopper 10 to the bottle A and this attaching structure is formed of a single length of wire bent intermediate its ends to provide a bight portion and a pair

of parallel legs 17 and 18, which extend longitudinally of the stopper and have their lower ends bent at right angles thereto and curved as shown at 19, to engage about the 5 outer surface of the neck B of the bottle A. The bight portion of the length of wire of which the fastening structure 16 is formed is sinuously bent, providing a substantially U-shaped portion 21, the bight portion of 10 which engages about the reduced portion 12 of the stem 11, directly beneath the shoulder formed at the upper end of this reduced portion. The lengths 22 of the bight portion of the wire 16, are bent outwardly and 15 angled so as to position the parallel legs 17 and 18 outwardly of the stopper or cork 13. A hook 23 is pivotally mounted on one side of the legs of the U-shaped portion 21 and the bill thereof is adapted to engage over 20 the leg of the U-shaped portion as clearly shown in Figures 1, 2 and 3 of the drawings, to securely bind the U-shaped portions 21 in engagement with the stem 11 and prevent accidental disconnection of these members. 25

In applying the improved bottle stopper to the bottle A, the stem 11 is inserted in the mouth of the bottle, and moved downwardly therein until the arcuate angled portions 19 engage the outer surface of the flange C after which the legs 17 and 18 are sprung outwardly, so as to spread the legs to permit these arcuate portions to pass over the annular flange C and the stopper is then 30 forced downwardly further into the bottle, after which the pressure upon the legs is released, allowing them to spring in their normal positions, causing the outer portions to engage about the neck B of the bottle, as 35 clearly shown in Figure 4 of the drawings. The cork or stopper 13, may then be forced firmly into the outlet or mouth of the bottle A forming a closure therefor. When it is desired to dispense some of the contents of 40 the bottle A, the stopper is moved outwardly until the arcuate portions 19 engage the under surface of the flange C as shown in Figure 2 of the drawings, at which time the upper portion of the groove 15 will be positioned beyond the flange C permitting the 45 liquid to be dispensed in drops from the bottle. To remove the stopper from the bottle, the legs 17 and 18 are spread, after the arcuate portions thereof are moved into engagement with the under surface of the flange C, so as to allow them to pass the flange, and the stopper may then be easily moved from 50 connection with the bottle A.

The improved stopper, when attached to 55 a bottle will prevent a person from accidentally drinking the contents of the bottle and therefore this stopper is particularly adapted for use in connection with bottles containing poison, and will effectively elimi-

nate the accidental suicide, or serious injury 65 to a person, who might accidentally swallow the contents of the bottle if one of the improved stoppers was not used in connection therewith.

Changes in details may be made without 70 departing from the spirit of this invention, but;

I claim:

1. The combination with a bottle including a neck, of a stopper therefor comprising 75 a non-absorbent stem, a cork carried by the stem, and means carried by the stem for engagement about the bottle neck for permitting a limited sliding movement of the stem in relation to the bottle neck and arranged 80 to prevent accidental disconnection of the stopper and bottle.

2. The combination with a bottle including a neck having a flange thereon, of a stopper therefor comprising a non-absorbent 85 stem, a cork carried by the stem, means carried by the stem for engagement about the bottle neck to prevent accidental disconnection of the stopper and bottle, said means engageable against said flange to limit the 90 relative outward movement of the stopper, said stopper provided with a longitudinally extending recess to permit the dispensing of the contents of the bottle.

3. In a bottle stopper, the combination, 95 of a relatively long non-absorbent stem, a cork detachably mounted about a portion of said stem, an attaching member carried by said stem and comprising a length of wire bent to form a pair of leg portions, the lower 100 ends of said legs being bent to provide angularly extending arcuate portions for engagement about a bottle neck.

4. In a bottle stopper, the combination, of a non-absorbent stem provided with a reduced portion near one end thereof, a cork mounted about said reduced portion, said stem provided with a longitudinally extending recess opening out at one end of the stem and terminating adjacent said reduced portion, and means carried by said stem for attaching the stopper to a bottle. 105

5. In a bottle stopper, the combination, 110 of a non-absorbent stem provided with a reduced portion near one end thereof, a cork mounted about said reduced portion, said stem provided with a longitudinally extending recess, means for attaching said stopper to a bottle comprising a length of wire bent to provide a stem engaging portion and a pair of legs, the free end portions of said legs being bent to provide right angularly extended arcuate portions adapted for engagement about a bottle neck. 115

6. As a new article of manufacture, a drop- 120 per attachment for bottles comprising a relatively long cylindrical stem of uniform diameter having a longitudinally extending 125

groove formed therein, a reduced neck formed upon the upper end of the stem and a bottle stopper or cork mounted about said reduced neck.

5 7. In a bottle stopper, the combination with a body, an attaching member carried by the body formed from a single strand of wire including a horizontally disposed resilient U-shaped portion, means carried by the

resilient U-shaped portion for forcibly urging the U-shaped portion into tight engagement with the body, a pair of depending legs formed on the U-shaped portion, and horizontally disposed arcuate arms formed on the lower ends of the legs for engaging about a bottle neck. 10 15

CHARLES F. GUARD.
